UNITED STATES PATENT OFFICE

MARGARET CHICHESTER HOLLAND, OF EXMOUTH, ENGLAND

NETTED FABRIC AND METHOD OF PRODUCING THE SAME

Application filed May 15, 1928, Serial No. 277,819, and in Great Britain October 10, 1927.

This invention relates to means and method of producing netted articles whereby an improved fabric or material of greater strength or more ornamental than heretofore produced by known methods of netting is possible.

The invention primarily consists in producing a netted fabric with triangular shaped meshes, instead of with meshes of, as is usual, a diamond, square or lozenge shape. The invention also consists in interweaving and interlocking two or more netted fabrics with triangular shaped meshes in order to produce a more effective fabric for use in fishing and like purposes.

The invention consists further in the employment for the purpose of producing a netted fabric of the above mentioned description of, and in addition to a netting needle 20 of ordinary construction, of a mesh-stick or mesh-sticks of the usual shape, but marked or divided in such a manner and as hereinafter described, so as to facilitate a net with the above mentioned triangular meshes being produced. In some cases a mesh-stick or mesh-sticks of triangular formation in cross section may also be employed.

According to this invention, it is proposed for example in one method, in order to produce a triangular shaped mesh to the netting to use a mesh-stick of the usual shape, but marked along one edge with a series of equidistant notches or like indications and along the other edge with a number of similar equidistant notches, but intermediate of the notches or marks on the upper edge.

In another method, it is proposed to use two such mesh-sticks similarly marked or notched, but one narrower than the other, the said mesh-sticks to be superposed one on the other in use.

In order to produce the above mentioned triangular mesh it is also required to use two separate threads or strings and two netting needles, or preferably, to wind two threads or strings on one needle.

In order that the invention may be clearly understood reference is made to the accompany drawings, in which,

Fig. 1 illustrates diagrammatically a small

portion of netting embodying the invention.

Fig. 2 illustrates diagrammatically a small portion of triangular meshed net formed according to the present invention.

Fig. 3 is a detail view showing the construction of the knot the extra thread introduced. 55

Fig. 4 illustrates an ordinary netting needle wound with two threads.

Fig. 5 illustrates an ordinary shaped mesh-stick marked with a series of notches or 60 marks.

Fig. 6 shows a mesh-stick of triangular shape in cross section.

Fig. 7 shows the formation of the triangular meshed net using only one mesh stick. 65

Fig. 8 shows the formation of the triangular meshed net using two superposed mesh-sticks of different widths.

Fig. 9 illustrates diagrammatically two interwoven and interlocked triangular meshed 70 nets.

Fig. 10 illustrates diagrammatically three interwoven and interlocked triangular meshed nets.

Fig. 11 illustrates a portion of a triangular 75 meshed net formed of narrow ribbon, raffia or like material, and

Fig. 12 illustrates a triangular meshed net interwoven or embroidered with strands or 80 silk, cotton, wool or other like material.

Referring to the drawings, in Fig. 1 is illustrated a small portion of netting embodying the invention, the various strands forming the net being knotted in by ordinary "fishermen's knots" 1.

In order to form a triangular meshed net as illustrated diagrammatically in Fig. 2, a needle 2 of the usual construction is used but wound with two threads or strings 3, 4, as indicated in Fig. 4, and a mesh-stick 5 90 also of the usual shape, but marked by means of a series of spaced and equidistant notches 6, 7, is also employed as indicated in Fig. 5, the notches 7 being arranged equidistant but intermediate of the notches 6. 95

One thread 8 is passed obliquely round the mesh-stick to form the foundation loops 9 in the usual manner, but the second thread 10 on the needle is passed parallel with the top edge of the mesh-stick 5 and knotted 100

in with the first thread at each notch 6 on the top edge of the mesh-stick as indicated at Fig. 7, the knot formed having the appearance indicated on an enlarged scale at Fig. 3.

5 In this method the thread 8 passing round the mesh-stick 5 forms the foundation loop 9 as usual and two sides of a triangle while the second thread 10 lying parallel with the top edge of the mesh-stick 5 between adjacent notches 6 forms the base.

10 As a modification of the above described method of forming a simple triangular meshed fabric, by using two mesh-sticks 11 and 12, one 12 narrower than the other 15 superposed as indicated at Fig. 8, a triangular meshed fabric may be produced in which the base 13 of the triangular mesh will be formed on the narrower 12 of the two superposed mesh-sticks, as clearly indicated in 20 Fig. 8.

Similar results may be attained by the use of a mesh-stick 5^a as shown in Fig. 6 of triangular shape in cross section having notches 6^a and 7^a.

25 Another construction of the triangular meshed fabric according to this invention consists in separately netting one triangular meshed fabric 14 as above described, and then to net, interweave and interlock a second similar triangular meshed fabric 15 as the netting proceeds as indicated at Fig. 9. A still further modification may consist of three similar netted, interwoven and interlocked fabrics 16, 17 and 18, as indicated at 35 Fig. 10.

It is also proposed to form the triangular meshed fabric of narrow ribbon, raffia or like material as indicated at Fig. 11, and to produce thereby a highly ornamental product 40 which may be used for a variety of decorative or personal uses.

By interlacing coloured threads, wools, silks or like materials 19 in a triangular meshed fabric as above described, in the manner indicated in Fig. 12, embroidery effects 45 may be obtained which will be of a highly decorative character.

Although approximately equilateral triangles have been indicated in the drawings 50 other forms of triangle may be produced, such as isosceles, scalene and the like, by suitably altering the spacing of the knots when being formed on the mesh-stick or by using the triangular mesh-stick shown at 55 Fig. 6.

A netted fabric produced according to the methods above indicated, owing to the oblique pull on all the threads forming the sides of the triangle, results in a much 60 stronger construction of fabric than with the ordinary type of netting and one less likely to be pulled out of shape. When produced in string, cord or the like, this construction of netting is more suitable for fishing nets, 65 hammocks and the like netted articles,

The triangular meshed netting also, if produced in finer materials, such as silk, ribbon, cotton or the like, is capable of being formed into very ornamental articles, such as table covers, curtains and the like.

70 By interweaving coloured cords, silk, ribbon or the like in the manner described, through the triangular meshes, various ornamental designs may be produced, rendering the fabric suitable for many decorative purposes.

I claim:—

1. The method of producing netted fabric consisting in winding upon a netting needle two independent strands successively forming parallel rows of foundation loops of one of said strands, the loops of each row being connected by knots to the loops of adjacent rows and connecting the knots uniting the foundation loops by the other strand, said strand being knotted in with the strand forming the foundation loops. 80

2. The method of producing netted fabric consisting in successively forming parallel rows of foundation loops of a continuous 90 strand by passing said strand about a mesh-stick having notches along both edges thereof, the notches along one edge being intermediate the notches along the other edge, the loops of each row being connected by knots 95 to the loops of adjacent rows as indicated by the notches along one edge of said stick and connecting the knots uniting the foundation loops by a supplementary strand knotted in with the strand forming the foundation 100 loops.

3. The method of producing netted fabric consisting in successively forming parallel rows of foundation loops of a continuous 105 strand by passing said strand about a mesh-stick, the loops of each row being connected by knots to the loops of adjacent rows and connecting the knots uniting the foundation loops by passing a supplementary strand about a mesh-stick relatively narrower than said other mesh-stick, and knotting this supplementary strand in with the strand forming the foundation loops. 110

4. The method of producing netted fabric consisting in forming a plurality of sets of 115 parallel rows of foundation loops, each set being formed of a continuous strand, the loops of each row of each set being connected by knots to the loops of adjacent rows of each set and connecting the knots 120 uniting the foundation loops of each set by a supplementary strand knotted in with the strand forming the foundation loops of the set with which said supplementary strands are respectively connected.

5. A netted fabric consisting of a plurality of parallel rows of foundation loops formed of a continuous strand, the loops of each row being connected by knots to the loops of adjacent rows, and a supplementary strand con- 125

necting the knots extending from knot to knot connecting the foundation loops and being knotted with the strands of said foundation loops respectively, whereby a triangular mesh is presented in said fabric.

6. A netted fabric consisting of a plurality of sets of interwoven parallel rows of foundation loops, each set formed of a continuous strand, the loops of each row of each set being connected by knots to the loops of adjacent rows of each set, and the foundation loops of each set being connected by a supplementary strand knotted in with the strand forming the foundation loops of the set with which the supplementary strands are respectively connected.
